MOBILE VERGE PLATE FOR KNITTING MACHINES

Carl Deitenbach, Jamaica, N. Y.

Application November 30, 1937, Serial No. 177,209

3 Claims. (Cl. 66—110)

This invention relates to knitting machines with special reference to the verge plates used in connection with the sinkerhead or loop forming devices for straight line knitting machines.

5 Among the several objects the more important are: in reducing strain of the mechanism, preventing undue wear; avoiding jack, sinker and worn plate lines in the fabric; preventing uneven knitting, and effecting very considerable 10 saving of sinkers, time and material.

More specifically the purpose of the invention is in the provision of a verge plate limitedly movable and resiliently pressed outward away from the sinker plate.

15 These objects are accomplished by the novel construction and arrangement of parts herein-after described and illustrated in the accompanying drawings, constituting an essential component of this disclosure, and in which:—

20 Figure 1 is a top plan view of the sinker head of a conventional type of knitting machine showing an embodiment of the invention in operative position.

Figure 2 is a plan view of the verge plate in 25 detail.

Figure 3 is a similar view of the sinker plate.

Figure 4 is an edge view of undulating spring interposed between the verge and the sinker plates.

30 Figure 5 is a front elevational view of the same.

Figure 6 is an enlarged transverse sectional view taken on line 6—6 of Figure 1.

Figure 7 is a similar sectional view taken on 35 line 7—7 of Figure 1.

Figure 8 is a transverse sectional view of the loop forming portion of the knitting machine.

Figure 9 is a similar sectional view showing the same parts in advanced position.

40 Figure 10 is another like view of the same as further advanced.

Referring in further detail to the drawings, the machine will be seen to include a frame composed of a center bed 15 extending the length 45 of the machine; on the rear flanged portion of the bed is secured a jack bed 16, and on top of its upright forward portion is a base bar 17, its lateral edges extending both forwardly and rearwardly as shown.

50 The bar 17 is plurally grooved transversely to slidably receive dividers 18 alternating with sinkers 19, the upper edges of these elements being engaged in corresponding grooves in the cap bar 20 of the sinker head.

55 Raised lugs 21 on the dividers 18 are engaged

in a catch bar 22 by an adjustable block 23 attached to cam actuated arms 24 moved rectilinearly by the machine elements. (Not shown).

Carried adjustably on the jack bed 16 are a series of spacer members or jack combs 25 held by a clamp bar 26 and spaced in conformity with the sinkers 19 whereby alinement is maintained. 5

A plurality of jacks 27 are pivoted on a rod 28 set in the spacers 25 and pressed forwardly by individual springs 29, their motion being limited by a stop bar 30. 10

The upper, forwardly curved ends of the jacks 27 are adapted to contact upstanding projections 31 at the rear ends of the sinkers 19.

A plurality of needles 32 are secured in a needle bar 33 held by a clamp 34 therein and actuated in a manner well known in the art. 15

The improvements consist in a novel form of verge plate 35 loosely held on the inclined upper surface of the cap bar 20 of the sinker head and 20 floatingly secured against rising by shoulder screws 36.

The verge plate is provided with substantially triangular openings 37 near its ends, through which extend pins 38 fixed in the cap bar 20. 25

The rear edge 39 of the plate 35 is downwardly flanged and positioned in spaced relation to the rear edge of the cap; in the space thus formed is inserted a thin flat spring 40, bent sinuously to produce a series of undulations 41, and its ends 30 42 turned angularly, its effect being to normally press the verge plate 35 rearwardly when it strikes the sinker projections 31, cushioning the contact. 35

Thus the constant pounding of the sinkers is minimized, reducing wear and vibration and distributing the shock to the machine.

As changes of construction could be made within the scope of the invention, it is intended that all matter contained in the foregoing description or shown in the accompanying drawings shall be interpreted as illustrative and not in a limiting sense. 40

Having thus described the invention, what is 45 claimed as new and desired to secure by Letters Patent, is:—

1. In a knitting machine having a sinker head provided with a cap bar and a plurality of divider and sinker elements movable transversely in grooves therebetween, said sinkers having raised projections rearwardly of the cap bar, a verge bar floatingly secured on said cap bar, said plate having a down-reaching flange entering the space between said bar and projections, and a 50 55

flat spring plurally undulated interposed between said flange and cap bar.

- 5 2. In a knitting machine having a sinker head provided with a cap bar and a plurality of divider and sinker elements movable transversely in grooves cooperatively formed therein, a verge plate having triangular openings, pins set into said head to extend into the mentioned openings limiting the movement of said plate, means to prevent rising of said plate, a down-reaching flange on said plate spaced from said cap, and resilient means disposed in the space therebetween to cushion the impact of said sinkers.
- 10

3. In a knitting machine having a sinker head provided with a cap bar and a plurality of divider and sinker elements slideable in grooves in said head and bar, a verge plate limitedly floatable on said cap bar, a flange on said plate spaced from the rear edge of said bar, and a thin flat spring bent to present a series of undulations disposed in the space between said flange and said bar, thereby to press said plate against said sinker elements.

CARL DEITENBACH.
